CUSHIONED RECEPTACLE AND CARBOY
THEREINOscar Z. Brewer, Spokane, Wash., assignor of
one-half to H. H. McNeill Lumber Co., Inc.,
New York, N. Y., a corporation of New York

Application December 12, 1944, Serial No. 567,827

4 Claims. (Cl. 217—54)

1

My invention relates to an improvement in carboy packages, namely, boxes or crates containing a carboy or other frangible container in which acids and other liquids are shipped.

It is essential that in a boxed carboy provision be made for preventing breakage of the carboy in transit, and in practice cushions of various types have been provided between the carboy and its box or crate.

The present invention provides an improved construction in carboy boxes, particularly with reference to the packing to be employed between the box and the sides of the carboy. The packing employed beneath the carboy and the construction employed at the top of the box may, so far as the present invention is concerned, follow conventional practice.

More specifically my invention provides a carboy box or crate in which cushions or pads are provided between posts at the corners of the box or crate and the side of the carboy, means which I believe to be new and novel in construction being provided for holding these cushions or pads against displacement and under compression against the side walls of the carboy.

In the accompanying drawings wherein I have illustrated one embodiment of my invention:

Fig. 1 is a sectional plan view of a carboy crate or box constructed in accordance with my invention; and

Fig. 2 is a sectional view taken on the line 2—2 of Fig. 1.

Referring to the drawings in detail: 2 designates a carboy box, crate or casing having four sides and a bottom, handholds 4 and skids 6. This construction is conventional.

Fitted within each corner of the box and nailed or otherwise permanently secured in place therein is a corner post 8. These posts are of wood, triangular in cross section, and smooth faced, with the base of the triangle or inner face 9 of each post facing the carboy. The carboy has been designated 10.

In accordance with conventional practice the carboy may rest upon cushions 12 carried by slats or strips 14 at the bottom of the box.

Between each of the corner posts 8 and the carboy or bottle 10 I provide cushions or packing 16 which are to bear against the carboy. These cushions are arranged in pairs, an upper and a lower cushion, at each box corner.

The cushions or packing 16, which are of resilient material, such as rubber—synthetic or natural—ground cork, felt, etc., are mounted in pairs on the smooth inner face 17 of a cushion

2

carrier 18. It will be seen and understood that there is a cushion carrier for each corner post. Each cushion carrier is of wood, extends substantially from bottom to top of the box 2, and is provided on its rear face 19 with a vertically extending continuous rib 20, lying intermediate the sides of the carrier, preferably centrally of the carrier.

The opposite face, that is, the front face of each cushion carrier is smooth and flat and parallel to the rear face and the cushions 16 are cemented or otherwise permanently secured thereto. Each carrier, as will be understood, is provided with an upper and a lower cushion.

The cushions are preferably so disposed upon the flat face of the cushion carrier as to be abreast of and contact the carboy 10 at the curve of the shoulder of the carboy and at the curve of the bottom of the carboy.

It will be appreciated from all of the foregoing that the cushion carriers extend vertically of the box 2 substantially from top to bottom of the box and are parallel to the smooth inner face 9 of each corner post.

In order that the cushions 16 may be placed under the necessary compression and that the carriers may not become displaced, I provide wooden spacer members 22, a pair for each carrier.

These members are simply straight wooden strips beveled slightly at their leading end adapted to be driven vertically of the box between the smooth face 9 of the corner posts and the rear face of the cushion carriers. A pair of spacers is provided for each carrier at each corner post, one spacer being located at one side of the rib 20 on the cushion carrier, and the other at the opposite side of the same rib.

The spacer members 22 are of the proper thickness to contact the smooth inner face 9 of the corner post and the smooth portion of the rear face of the cushion carrier and to force the cushion carrier toward the carboy thereby to force the cushions into contact with the carboy under the desired compression. The spacer members are also of the proper width so that the outer edge 24 of each spacer member will contact the box side, while the inner side 26 contacts the side of the rib 20 on the cushion carrier. In this way not only are the cushion carrying members held in position against lateral shifting but rocking of the same is prevented so that I am always assured of proper cushion contact with the carboy or other receptacle which is to be protected.

It will be appreciated that in my construction

the elasticity of the cushions and the inherent elasticity of the wood of the various components of my package are relief upon to absorb all shocks to which the package may be subjected and which otherwise might fracture the carboy.

It is to be understood that changes may be made in the details of construction and arrangement of parts hereinabove described without departing from the spirit and scope of my invention.

What I claim is:

1. In combination a box, a receptacle therein, cushions between the box and the receptacle, cushion carriers for said cushions, a central rib along the outer face of each cushion carrier, box corner posts corresponding in number to said cushion carriers, and individually removable members insertible between the cushion carriers and the corner posts at each side of said ribs, for moving the carriers toward the receptacle to place the said cushions under compression against the sides of said receptacle, said individually removable members constantly contacting the sides of said ribs and the immediately adjacent box sides, thereby positively preventing lateral shifting and tilting of the removable members and said cushion carriers.

2. In combination a box, a receptacle therein, cushions between the box and receptacle, cushion carriers to the face of which said cushions are attached, a vertically extending rib on the outer face of each of said cushion carriers and spaced from the edges of the carrier, a box corner post between the box and the ribbed face of each of said cushion carriers, and a removable member between the inner face of each of said corner posts and the ribbed face of each of said cushion carriers, said removable members being of such thickness as to force the carriers inwardly to place the cushions under compression against the receptacle sides, and of such width as constantly to contact the sides of the carrier ribs as well as the adjacent sides of the box positively to prevent lateral shifting and tilting of the removable members and the cushion carriers.

3. In combination a box, a receptacle therein, a cushion carrier at each corner of the box, an abutment on the outer face of each carrier, a pair of cushions mounted on the inner face of each

carrier, a smooth faced corner post at each box corner, a pair of separately removable members at each corner of the box between the corresponding corner post and cushion carrier and contacting said post and carrier throughout their length for forcing the carriers inwardly to compress said cushions against the receptacle sides, the two members constituting each pair of said separately removable members being so disposed at each side of the corresponding carrier abutment and in constant contact therewith and with the adjacent box sides thereby positively to prevent lateral shifting and tilting of the removable members and cushion carriers.

10 4. In combination a box, a receptacle therein, a post in each corner of the box triangular in cross section, two sides of each of said posts abutting two adjacent box sides, the third side of each post being smooth and facing said receptacle, a cushion carrier between the smooth face of each corner post and said receptacle, a cushion secured to the inner face of each of said carriers for engagement with said receptacle, a vertically extending rib on the outer face of each of said carriers and spaced from the side edges of the carrier, and strips individually insertible between the outer face of each cushion carrier and the smooth face of each corner post, each of said strips constantly contacting a side of the carrier rib, the immediately adjacent box side, the smooth face of the corner post and the rear face of the cushion carrier, for separating the cushion carriers and their respective corner posts sufficiently to hold the cushions under compression against the receptacle sides, and positively to prevent lateral shifting and tilting of the cushion carriers and strips.

OSCAR Z. BREWER.
